UNITED STATES PATENT OFFICE.

CHARLES C. MENGEL, OF LOUISVILLE, KENTUCKY, ASSIGNOR TO MENGEL BOX COMPANY, OF LOUISVILLE, KENTUCKY, A CORPORATION OF NEW JERSEY.

WIRE-BOUND BOX.

No. 927,261.

Specification of Letters Patent.

Patented July 6, 1909.

Application filed August 13, 1908. Serial No. 448,324.

To all whom it may concern:

Be it known that I, CHARLES C. MENGEL, a citizen of the United States, residing at Louisville, in the county of Jefferson and State of Kentucky, have invented certain new and useful Improvements in Wire-Bound Boxes, of which the following is a specification.

My present invention relates to improvements in wire-bound boxes, and especially of that class in which the blanks, constituting the four sides of the box, are assembled and secured in position relative to each other by reinforcing wires prior to being folded into box-like form, the construction and advantages of which will be hereinafter set forth, reference being had to the annexed drawings, wherein:

Figure 1 is a perspective view of the four blanks which constitute the sides of the box, showing the cleats attached thereto and the binding wires also in position; Fig. 2 a perspective view of the box in its assembled form, the ends or heads being broken away; Fig. 3, a transverse sectional view, on the line *a—a* of Fig. 2; Figs. 4 and 5, detail perspective views showing the form of the joint between the ends of the cleats and the edges of the sheets which constitute the sides of the box; and Fig. 6 a perspective view of a portion of the box showing the binding wire secured to the box in line with the cleats.

The main object of the present invention is to so form and connect the various sections which go to make up the box-blank that when brought to their final position a box of superior strength and likewise one having close joints is produced.

A further object of the invention is to provide a joint of peculiar form at the abutting ends of the cleats, the same being in effect a combined square and miter joint which provides for all strains and prevents the breaking of the sides. Such a construction, furthermore, permits the introduction of one or more nails from the outside through each of the joints, thereby making the package quite rigid and securely locking the parts together.

With these and other objects in view, a description of the invention will be given.

The sides 1, 2, 3 and 4, two of which, of course, constitute the top and bottom of the box although for the purpose of clearness they will hereinafter be referred to as

"sides", are each composed of a board or a plurality of boards, the adjacent edges of which are beveled at an angle of 45°, so that when the parts are brought together to form a box the edges will come into close contact and make a tight joint, one board or side mutually sustaining the other board or side.

To the outer edge of each side is secured a cleat 5, preferably formed of three layers of veneer, 6, 7, 8. The outermost layer in each instance is designated by the numeral 6, and the innermost layer by the numeral 8. Said cleats are alike in form, and the innermost layer is square at each end, one end, 9, extending to the edge of the bevel formed upon the sheet to which it is attached, and the adjacent end of the opposite cleat stopping short of the edge of the sheet a distance equal to the width of member 8, said short end being designated by the numeral 10, 75 Figs. 4 and 5. The outermost and intermediate layers, 6 and 7, are cut away or beveled, as clearly seen in said figures, at an angle of 45°, the edges being coincident with the bevel formed upon the edges of the side members. It will, of course, be understood that in so far as my invention is concerned, this arrangement may be reversed and the projecting squared end 9 may appear upon the outside, and the short end 10 likewise 85 upon the outside.

By having the grain of the intermediate layer 7 extend crosswise, or at right angles to the longitudinally-extending grain of the layers 6 and 8, it will be seen that the grain in the extension or squared end 9 and in the long beveled end 11 of the outermost layer 6 will run lengthwise of the stock, and consequently when the parts are brought together nails 12 may be readily driven through the overlying parts without danger of splitting said parts and otherwise weakening the joint.

Suitable binding wires 13 are stapled or otherwise secured to the sides 1 to 4 inclusive in a manner well known to those skilled in the art. Preferably the blanks are shipped in their flat form, being brought to the position shown in Fig. 2 with the heads 14 and 15 inclosed thereby, after which the ends of the wires will be twisted together, suitably bound or otherwise secured to the structure.

The square shoulders formed by the construction above set forth take up any direct strain or thrust which may be placed upon the

any side of the box, thus relieving the edges of the sides from undue strain and preventing any torsional or twisting action taking place in the box structure.

- 5 By the employment of the combined beveled and square end cleats the object just set forth is accomplished, in addition to which a support for the sides is provided to the extreme outer edges thereof, whereby they 10 may be tacked to the cleats and thus securely held in position. Furthermore, the sides being supported to their meeting-edges there is no danger of their being crushed, especially where they are formed of light material, such as veneer or the like. It will likewise be seen that by forming bevels upon the ends of the cleats, coincident with the bevels of the abutting edges of the sides, the parts when brought to position will form a 15 tight joint at the corners or edges of the box, and that there is little or no danger of the binding wires breaking down the edges of the sheets when the parts are folded and the wires tightened.
- 20 25 It is manifest that instead of forming the cleats of veneer they may be made from solid material, but for obvious reasons veneer is preferable.

It is, of course, conceivable that in so far 30 as the generic construction of the cleats is concerned, they may be employed with sides of a form different from that illustrated; as, for instance, a single sheet of veneer might be used for all of such sides, or the sides may be 35 extended beyond the ends of the cleats to form a square joint when the parts are brought to position, as is common in the art. The bevel-edged construction of the sides is, however, preferred for obvious reasons.

40 In Fig. 6 the binding wire is shown secured to the box in line with the cleats, the staples passing through the sides into the cleats.

Having thus described my invention, what 45 I claim is:

1. In a knock-down box, the combination of a plurality of sides, the adjacent edges of which are beveled so as to form a close joint when brought to position; and a pair of cleats 50 carried by each side, each cleat having a beveled and a square portion at each end, said beveled and square portions of each end contacting and forming a close joint with the corresponding portions of the next adjacent cleat when the parts are brought to their closed or assembled position.
2. In a knock-down box, the combination of a plurality of sides; and a pair of cleats

secured to each side, each cleat being provided at one end with an outwardly-projecting square portion and a beveled face, and at its opposite end with a square portion which stops short of the edge of the side a distance equal to the width of the cleat, and likewise provided with a beveled portion 65 complementary in shape to the beveled portion formed upon the opposite end, whereby when the parts are brought to their assembled or closed position the end of said square projecting portions will abut against the 70 face of the next adjacent side of the box, while the beveled portions will contact with each other and bring the parts to their proper position.

3. In a knock-down box, the combination 75 of a plurality of sides, the adjacent edges of which are beveled at an angle of 45°; and a pair of cleats secured to each of said sides, each cleat having a beveled portion at each 80 end which is formed coincident with the bevel upon the edges of the sides, and with a projecting square portion at one end; the end of said square portion terminating at the inner edge of the beveled portion of the side, the opposite end of the cleat being likewise 85 provided with a square portion which terminates short of the beveled portion a distance equal to the width of the cleat.

4. In a knock-down box, the combination 90 of a plurality of sides; binding wires for securing the same together; a pair of cleats for each of said sides, each end of each cleat being provided with a beveled face and a square portion adapted to coöperate and form a close joint with the end of the next 95 adjacent cleat; and fastening devices passing through the overlapping ends of the cleats.

5. In a knock-down box, the combination 100 of a plurality of sides; binding wires for securing the same together; and a pair of cleats for each of said sides, each end of each cleat being provided with a beveled face complementary in form to the beveled end of the next 105 adjacent cleat, and likewise provided with a square portion lying to one side of the beveled portion and adapted to bear against and form a joint with the square end of the next adjacent cleat.

In testimony whereof I have signed my name to this specification in the presence of 110 two subscribing witnesses.

CHARLES C. MENGEI.
